DESIGN FOR A TELEPHONE INDEX CASE

Richard M. Hyde, Los Angeles, Calif., assignor to Security Products Company, a firm composed of Harry A. Morgan, O. E. Boyd, and C. E.
Sawyer, Los Angeles, Calif.

Application June 24, 1936, Serial No. 63,452

Term of patent 3½ years

To all whom it may concern:

Be it known that I, Richard M. Hyde, a citizen of the United States and residing in Los Angeles,
in the county of Los Angeles and State of California,
have invented a new, original, and ornamental Design for a Telephone Index Case, of which the following is a specification, reference being had to the accompanying drawing, forming part thereof, in which:

Figure 1 is a perspective view of a telephone index case showing my new design as seen from the front and one side thereof, and Fig. 2 is a perspective view of the case as seen from the rear and one side thereof.

I claim:

The ornamental design for a telephone index
case as shown.

RICHARD M. HYDE.
